United States Patent Office.

AMOS T. PEIRCE, OF FAIR HAVEN, MASSACHUSETTS.

Letters Patent No. 92,467, dated July 13, 1869.

IMPROVEMENT IN BOWLING-ALLEYS.

The Schedule referred to in these Letters Patent and making part of the same.

To all whom it may concern:

Be it known that I AMOS T. PEIRCE, of Fair Haven, in the county of Bristol, and State of Massachusetts, have invented a new and improved Bowling-Alley or Table; and I do hereby declare that the following is a full, clear, and exact description thereof, reference being had to the accompanying drawings, making a part of this specification, in which—

Figure 1 is a perspective view of a bowling-table having my improvements applied to it.

Figure 2 is a longitudinal section taken in a vertical plane through the centre of the improved bowling-table, showing a portion of the return-trough broken away to expose a spring-ball stop at the lower end of said trough.

Figure 3 is a top view of the perforated centring-board for the pins.

Similar letters of reference indicate corresponding parts in the several figures.

This invention relates to certain novel improvements which are applicable to bowling-alleys and bowling-tables, and which are designed for enabling a person standing at the end of a table or alley from which the balls are rolled, to set up any one or all of the pins which have been knocked down, and adjust them in the proper places, and at the same time bring the ball or balls which may have been rolled, back to place from which it or they may be conveniently taken, as will be hereinafter explained.

To enable others skilled in the art to understand my invention, I will describe its construction and operation.

In the accompanying drawing I have represented my invention applied to a table, of which A is the rolling-bed upon which the pins a a are placed, and D the body of this table, which latter is mounted upon legs D'. In practice the bed A may be made of any required length, and mounted upon legs as a table, or laid down in the manner of a permanent alley.

In rear of the pin-bed A', a pit, B, is made, which is properly cushioned, and provided with a bottom that inclines towards a hole, p, shown in dotted lines, fig. 2. This hole p leads down into the elevated end of a trough, E, which extends forward and terminates at a stop, R, which is located in the bottom of a vertical chamber, F', of a box, F. In this chamber F' a box, N, is moved up and down by a pulley, g, and suspension-chain or cord f, which box is open at top and one end, and designed for elevating balls from the front end of trough E, and depositing them in the front end of a trough, C, which may be raised above the level of the bowling-bed A.

The stop R of the front end of the lower trough E is constructed with a ledge, r, and applied to a long spring, T, as shown in fig. 2. This spring T will thrust up the stop R, in front of the trough E, when relieved from the weight of box N, and prevent balls,

which may be in said trough, from rolling off when the box N is not in a position for receiving the balls. When the box N is fully depressed, its weight bearing upon the ledge r, of the said stop R, will depress this stop far enough to allow balls to roll from trough E into said box.

By grasping the handle g', on pulley g, and turning this pulley, the box N can be elevated to a proper height for discharging balls from it, and depositing them into the front end of the elevated trough C. The lip e, on the front end of this trough C, will catch over the open end of the box N, and cause this box to tilt sufficiently to deliver its balls into said trough, as shown in fig. 2. The trough C, extends back to the rear end of the table, and, being inclined forward, it may be used for conducting balls from the rear to the front end of the table, when it is not desired to use the trough E and box N for this purpose. Without the box N, arranged either at the front or rear end of the table or alley, the service of a person stationed in the pit B, will be required to lift the balls by hand into the elevated end of the trough C, in order to get them back to the front end of the table. The pulley g is applied to a standard, P, secured to one side of the table near its front end, and there is also attached to this pulley g, a cord, f', which rises and passes over a pulley, h, at a proper height, and is thence conducted to, and passes over a pulley, m', and carried down and fastened to a vertical rod, n. The pulley m' is applied to a pendant, V, which is secured centrally to an arched bridge, K, which is secured upon a rectangular frame, I, which is mounted upon the upper ends of four vertical posts J, which rise from the side pieces of the table D.

The frame thus described supports the pulley-pendant V at an elevated point over the centre of the pin-bed A', as shown in the drawings.

The rod n is secured perpendicularly to the centre of a horizontal board, G, through the four corners of which the vertical posts J pass loosely, and afford guides for keeping the said board in a horizontal position while it is being raised or depressed by the cord or chain f'. Beneath this board G, is another board H, which is guided by posts J, in the same manner as these posts guide the board G, and which is suspended from a pulley, m, in pendant V, by a rod, k, and a cord or chain h, which passes over said pulley m, and is attached to the upper end of rod n, on board G, as shown in figs. 1 and 2.

By this arrangement and mode of suspending the two boards G and H, it will be seen that when the board G is elevated, by drawing down the tassel f' on cord or chain f', or by turning pulley g in the direction indicated by the arrow upon it in fig. 2, the lower board H will descend by its own gravity until it assumes the position shown in fig. 2; and by releasing tassel f' or pulley g, as the case may be,

the board G will descend by its own gravity and lift the board H, until these two boards meet in the position shown in fig. 1. The board H, being lighter than the board G, the latter, when released, will cause the former to ascend in the same ratio as the board G descends.

The pins *a*, when properly set up on their bed A', are arranged in the form of an equilateral triangle, and each pin *a* is attached, by a small cord, *b*, of a given length, to the lower end of a pin which passes freely through the board G, and is supported upon a light spring *b'*, on top of the said board, as shown in figs. 1 and 2. The spring-supports *b'*, to which cords *a* are attached, are arranged in vertical lines, and disposed in a similar manner to the pins *a*, when properly set up on their bed. The cords *b*, which are of an equal length, pass from their spring-pins on board G, down through holes *i*, made through the board H, and are attached centrally to the upper ends of the pins *a*. The holes *i*, which are made through the board H, correspond in number and arrangement to the spring-supports *b'*, and also the pins *a*, when the latter are set up, and the vertical axis of each hole *i* should coincide with the vertical axis of its pin *a*, when the latter is brought to an upright position in its proper place on bed A'.

Operation.

To set up the pins *a*, the bowler at the front end of the table or alley pulls the tassel *f*', which will elevate the board G high enough to suspend all the pins *a*, a short distance above their bed A', as shown in fig. 2, and bring their upper ends into their respective holes *i*, through board H, which latter will be depressed to receive and steady said pins, simultaneously with the ascent of board G. The tassel *f*' is then released, when board G will descend, raise board H, leave the pins *a* in their proper places upon the pin-bed A', and slacken the pin-cords *b*, so as to allow the pins to fall readily when struck by a ball bowled from the front end of the table.

If it is desired to lift balls from trough E and deposit them into the trough C, during the act of setting up the pins *a*, the bowler turns pulley *g* in the direction

indicated by the arrow in fig. 2, thus winding the cords *f* and *f*' upon this pulley, which will elevate box N and deposit balls into the trough C, at the same time cord or chain *f*' is drawn down and the pins set up.

Having described my invention,

What I claim as new, and desire to secure by Letters Patent is—

1. The construction of a bowling-table or alley with a pit, B, having an inclined bottom leading into an inclined trough, E, which trough is provided at its depressed end with a spring-stop, R, and an elevator, N, whereby balls which have been bowled at the pins, will return towards the front end of the table or alley, and may be raised and deposited into a receptacle, C, substantially as described.

2. The spring-stop R, constructed with a ledge *r*, and applied to the depressed end of a ball-trough or conveyer, E, in combination with an elevator, N, substantially as described, and for the purposes set forth.

3. The elevated receiving-trough C, provided with a tilting-lip, *c*, in combination with a ball-elevating box, N, substantially as and for the purposes described.

4. The vertically-movable suspension-board G, having the pins *a* connected to it by cords *b*, and springs *b'*, in combination with the vertically-movable perforated centring-board H, said boards being suspended, guided, and operated, substantially as and for the purposes described.

5. The combination of setting-up devices, constructed so as to operate substantially as described, with ball-returning and lifting devices; said parts being connected to a pulley, *g*, or its equivalent, in such manner that the two operations of setting up the pins *a*, and lifting the balls, can be effected at one and the same time, substantially as described.

6. Pins, *a*, which are hung from a setting-up board, G, in combination with a vertically-movable perforated centring-board, H, substantially as described.

AMOS T. PEIRCE.
